TENSION CONTROL SYSTEM

Willard G. Cook, Wilkinsburg, Pa., assignor to
Westinghouse Electric & Manufacturing Com-
pany, East Pittsburgh, Pa., a corporation of
Pennsylvania

Application September 8, 1938, Serial No. 228,928

7 Claims. (Cl. 80—35)

My invention relates, generally, to tensioning devices and, more particularly, to systems for maintaining predetermined tensions on a strip of material as it passes between adjacent work devices.

In the production of sheet steel, it is customary to pass the steel in the form of a strip through a plurality of reducing rolls simultaneously and to subject the strip to front and back tension as it passes through the reducing rolls.

A very successful system for providing strip tension in a strip rolling mill is disclosed in the copending application of G. P. Lessmann, Serial No. 133,419, filed March 27, 1937, now Patent No. 2,189,609, issued February 6, 1940, and having a common assignee with the present application. This system comprises, generally, an idling roller which is caused to bear against the strip to deflect it from its normal pass line and thus subject the strip to tension. The operating system for the tensioning device is so arranged as to provide a predetermined range of strip tensions within a given range of strip deflection, the deflection of the strip being kept within a given range by automatic speed control of the reducing rolls by means of a vibrating regulator.

Such strip tensioning systems that utilize a regulator of the vibrating type do not have the speed of response, the wide range of regulation, the simplicity, and low cost of manufacture, installation and maintenance that is required in some rolling mills.

It is an object of my invention, therefore, to provide an improved control system for a strip tensioning device.

Another object of my invention is to provide a control system for a strip tensioning device which shall function to provide rapid response to changes in speed and tension conditions and function to quickly correct any of these conditions within a wide range of degrees of required correction to thereby maintain, as near as possible, the desired tension conditions on the strip.

Another object of the invention is to provide a control system for a strip tensioning device which shall be simple and efficient in construction and operation and inexpensive to manufacture, install and maintain.

These and other objects and advantages of my invention will be apparent from the following detailed description taken in connection with the accompanying drawings, in which:

Figure 1 is a diagrammatic representation of a portion of a strip rolling mill embodying the

principal features of a preferred embodiment of my invention; and

Figs. 2 and 3 are diagrammatic representations of strip rolling mills embodying modifications of my invention. 5

In practicing the preferred form of my invention shown in Figs. 1, 2 and 3, in which like parts are designated by like reference characters, I provide, generally, a tensioning device 10 disposed to deflect the strip 12 from its normal pass line as it passes in the direction of the arrow between two adjacent work devices, such as reducing rolls 14 and 16. The tensioning device 10 functions to maintain a desired tension on the strip 12 within a predetermined range of 15 strip deflection. The deflection of the strip 12 by the tensioning device 10 is kept within the desired range by speed control of the drive motor 18 for the rolls of the roll stand 16. The speed of the drive motor 18 is controlled by controlling the excitation of an exciter generator 20, which provides the excitation current for the motor 18. The excitation of the exciter generator 20 is controlled by a regulator 22, which is disposed to be actuated in accordance with 20 the variations in the deflection of the strip 12 by the tensioning device 10. 25

Referring to Fig. 1 for a detailed description of the preferred embodiment of my invention, the tensioning device 10 comprises a bell crank 30 30 having arms 26 and 28 and pivotally mounted on the support 30. An idling roller 32 is rotatably mounted upon the arm 26 to bear against the strip 12 and to thus tension the strip by deflecting it from its normal pass line between the 35 roll stands 14 and 16. A piston 34 acts upon the bell crank arm 28 to force the tensioning roller 32 against the strip 12, under the influence of fluid pressure which is maintained at a substantially constant amount by means of a 40 pressure regulating valve 36, which is connected between the pressure fluid reservoir and the piston 34. The pressure regulating valve 36 may be adjusted to provide any desired constant pressure acting upon the piston 34 by adjustment of the energization of the solenoid 38 by 45 means of the rheostat 40.

As is explained in detail in the above-referred to application Serial No. 133,419, the angular displacement of the bell crank arms 26 and 28 is 50 substantially 51°, and when the bell crank arm 28 is maintained substantially parallel to the normal pass line between the roll stands 14 and 16 and a substantially constant force is applied to the bell crank arm 28 by the piston 34, the 55

strip 12 will be subjected to a substantially constant tension by the tensioning roller 32 within a limited range of strip deflections.

The bell crank 24 is connected by means of 5 a shaft 42 to rotate a synchro-tie transmitter unit 44, which in turn is electrically connected to operate the synchro-tie receiver unit 46 in a well-known manner. The synchro-tie receiver unit 46 is mechanically connected to actuate the 10 cam 48 by means of a shaft 50.

A stack of elongated conducting strips 52 is provided, and these strips are insulated from each other by insulating members 54. Each of the strips 52 is provided with a contact element 15 56 extending to each side of the strip, each of the contact elements 56 being disposed opposite the contact element on the adjacent strip so that contact between each strip and its adjacent strip will be made when the strips are moved 20 closely together. The strips 52 are made of spring material and are so dimensioned and so disposed with respect to a stop block 58 as to permit their ends to engage the block 58 and hold the strips in spaced relation with each other. 25 The cam 48 acts upon an arm 60, having a pivotal support 62, against the bias of a spring 64. A pin 66 is mounted upon the arm 60, as shown, so as to engage the uppermost strip 52 and move it into contact relation with the next strip and to 30 thus move the successive strips into contact relation with their adjacent strips.

A resistance element 68 has several taps, as shown, each connected to one of the strips 52 so that as the strips are moved in contact relation with each other the sections of the resistance element 68 connected with the strips which are in contact with each other will be short-circuited, thus decreasing the effective resistance of the resistance element 68. The resistance element 68 35 is connected in series circuit relation with the field winding 70 of the exciter generator 20, and an adjustable resistance 71 to a suitable source of direct current as shown. Thus the excitation of the exciter generator 20 and, therefore, its output 40 potential will be varied by the regulator 22 in accordance with the degree of deflection of the strip 12 by the tensioning device 10. The adjustable resistance 71 is provided to make any desired adjustment in the output potential of the 45 exciter generator 20. The exciter generator 20 is continuously driven at a substantially constant speed by any suitable motor 72 and has its armature connected in series circuit relation through the adjustable resistance 74 with the field winding 76 of the drive motor 18 for the roll stand 16.

Thus the speed of the motor 18 may be adjusted by the adjustable resistance 74 and will also be varied in accordance with variations in the output potential of the exciter generator 20.

In the operation of the device of Fig. 1, the tensioning device will operate to maintain a substantially constant tension upon the strip 12, while the deflection of the strip is maintained between predetermined limits. If, for any reason, 65 the amount of slack in the strip 12 between the roll stands 14 and 16 should decrease, it will be seen that the bell crank 24 of the tensioning device 10 will be rotated in a counter-clockwise direction, and this movement will be transmitted 70 through the synchro-tie sending and receiving units 44 and 46 to the cam 48, which will cause a downward movement of the pin 66. The downward movement of the pin 66 will cause a number of the strips 52 to be moved away from the 75 block 58 and so that their contact elements 56

will be moved into engagement with each other to short-circuit a number of the sections of the resistance element 68, the number depending upon the amount of the change of the deflection of the strip, to thus increase the excitation of the exciter generator 20 and in turn increase its output potential. This increase in the output potential of the exciter generator 20 will increase the excitation of the motor 18 which will cause the motor to decrease its speed, thus permitting 10 an increase in the slack of the strip 12 between the roll stands 14 and 16 and, therefore, an increased deflection of the strip 12 by the tensioning device 10. In a similar manner, the speed of the motor 18 will be increased by an increase in 15 the deflection of the strip 12 by the tensioning device 10 to bring the deflection of the strip 12 back to within the desired predetermined limits.

In the tensioning control system of Fig. 2, a stack of resistance plates 78 is provided, and each 20 of these plates is separated from the adjoining plate by a metallic contact plate 80. Each of the resistance plates 78 has mounted thereon near one end a contact element 82, the contact elements 82 being disposed to engage each other 25 successively as the stack of plates is rocked in a counter-clockwise direction with the stack of contact plates 80 serving as a pivot point. An arm 84 is connected to be rotated by the shaft 50, and has mounted thereon the pin members 86 and 30 88 which bear upon a metallic plate 90 which is mounted above the stack of resistance plates 78. Each of the resistance plates 78 has an insulating plate 91 mounted thereon which prevents electrical contact between the right-hand 35 ends of the plates 78.

As the plate 90 is rocked in a counter-clockwise direction by the arm 84, it will be seen that the contact element 82 of the plate 90 and the uppermost resistance plate 78 will engage, and as the 40 stack is further rocked in the counter-clockwise direction, successive contact elements 82 will engage each other, thus providing a series of short circuits for the stack of resistance plates. As the resistance plates 78 are rocked, the contact resistance between the plates 78 and the contact plates 80 is decreased. Thus, the rocking of the arm 84 in the counter-clockwise direction will both decrease the contact resistance between the series of contact plates 80 and the resistance 45 plates 78 and successively short out these contact resistances, so that the effective resistance of the stack of plates will be decreased as the arm 84 continues to rotate in the counter-clockwise direction. The lowermost resistance plate is connected to a suitable source of direct current, as shown, and the metallic plate 90 is connected in circuit with the field winding 70 of the generator 20 and a suitable adjustable resistance 71 to the other side of the source of direct current.

The operation of the tensioning control system shown in Fig. 2 is similar to that described in connection with the system shown in Fig. 1, the regulation of the speed of the drive motor 18 to maintain the degree of deflection of the strip 12 within the desired predetermined limits being controlled by the regulator 22, as hereinbefore described, in response to variations in the angular displacement of the tensioning device 10 with respect to the strip 12.

The tension regulating system of Fig. 3 is generally similar to those shown in Figs. 1 and 2, and includes an arm 92 pivotally mounted on a support 93 and biased against the cam 48, which is actuated by the synchro-tie receiver unit, by a

spring member 94. The arm 92 is connected through a rod 96 to vary the compression force applied to a rheostat 98 of the carbon-pile type comprising a stack of resistance plates 100. In 5 this device, the effective resistance of the rheostat 98 will be varied by variations in the deflection of the strip 12 by the tensioning device 10 through the action of the cam 48 upon the arm 92. The rheostat 98 is connected in series 10 circuit relation with the field winding 70 of the exciter generator 20, and the variation of its effective resistance will thus vary the excitation of the exciter generator 20 to in turn vary the speed 15 of the motor 18 by controlling its field excitation.

In the operation of the system of Fig. 3, it will be seen that the deflection of the strip will be maintained within predetermined limits through the action of the regulator 22 upon the 20 excitation of the drive motor 18 of the roll stand 16.

In the discussion of the operation of these tension control systems, it has been assumed that the strip 12 is moving in the direction shown by 25 the arrow adjacent the strip, and that the speed of the roll stand has been maintained constant, thus requiring that any changes in the amount of slack in the strip 12 between the roll stands 14 and 16 be varied by means of speed variation 30 of the drive motor 18 for the roll stand 16. It is to be understood that it is within the scope of this invention to control the speed of the drive motor for the roll stand 14 in a similar manner instead of the drive motor 18 of the roll stand 35 16, or that the drive motors for both roll stand 14 and roll stand 16 may be controlled by my tensioning control device.

It will be seen that I have provided a simple, efficient and inexpensive control system for maintaining predetermined adjustable tensions on a 40 strip of material as it passes between adjacent work devices which will function to return the strip to the desired tension should any deviation from this tension occur, and which will quickly 45 and efficiently function to return the strip to the desired tension over a wide range of variations from this desired tension.

In compliance with the requirements of the patent statutes, I have shown and described herein 50 in the preferred embodiments of my invention. It is understood, however, that the invention is not limited to the precise constructions shown herein, but is capable of modification by one skilled in the art, the embodiments herein shown being merely illustrative of the principles of my 55 invention.

I claim as my invention:

1. In a system for subjecting a strip of material to tension as it passes between adjacent roll stands of a strip rolling mill, comprising a tensioning roller disposed to be made to bear upon the strip to deflect it from its normal pass line between the roll stands and thus subject the strip to tension, means for actuating said roller 60 to bear against the strip including means for automatically varying the transverse force applied to the strip by the roller in accordance with its strip deflecting operating position to subject the strip to a substantially constant tension, an 65 electric drive motor for the rolls of one of the stands, a variable voltage generator for exciting said drive motor, a resistor connected in excitation controlling relation with said generator, and means responsive to variations of operating position of said tensioning roller for controlling said 70

resistor, thereby to maintain the relative speeds of the sets of rolls of the roll stands such as to hold the tensioning roller within predetermined operating limits.

2. In a system for subjecting a strip of material to tension as it passes between adjacent roll stands of a strip rolling mill, comprising a tensioning roller disposed to be made to bear upon the strip to deflect it from its normal pass line between the roll stands and thus subject the strip to tension, means for actuating said roller to bear against the strip including means for automatically varying the transverse force applied to the strip by the roller in accordance with its strip deflecting operating position to subject the strip to a substantially constant tension, an electric drive motor for the rolls of one of the roll stands, a carbon-pile type rheostat connected to control the speed of said drive motor, and means for varying the effective resistance of said rheostat in accordance with the variations in the degree of deflection of the strip by said roller, whereby, the deflection of the strip by the roller is kept within predetermined limits.

3. In a system for subjecting a strip of material to tension as it passes between adjacent roll stands of a strip rolling mill, comprising a tensioning roller disposed to be made to bear upon the strip to deflect it from its normal pass line between the roll stands and thus subject the strip to tension, means for actuating said roller to bear against the strip including means for automatically varying the transverse force applied to the strip by the roller in accordance with its strip deflecting operating position to subject the strip to a substantially constant tension, an electric drive motor for the rolls of one of the roll stands, a resistor connected in speed controlling relation with said drive motor, a plurality of flexible members arranged with corresponding ends clamped in fixed relation and connected to separate points along said resistor, said fixed ends being insulated from one another, the other ends of said flexible members being free to move, a movement limiting stop against which the free ends of said flexible members are biased for positioning them in spaced relation, and means controlled in accordance with the degree of deflection of the strip for actuating said flexible members from engagement with said stop and into circuit closing engagement with adjacent members to short-circuit selected portions of said resistor to thereby limit the degree of deflection of the strip by said tensioning roller.

4. In a system for subjecting a strip of material to tension as it passes between adjacent roll stands of a strip rolling mill, comprising a tensioning roller disposed to be made to bear upon the strip to deflect it from its normal pass line between the roll stands and thus subject the strip to tension, means for actuating said roller to bear against the strip including means for automatically varying the transverse force applied to the strip by the roller in accordance with its strip deflecting operating position to subject the strip to a substantially constant tension, an electric drive motor for the rolls of one of the roll stands, a stack of resistance plates, a metal contact plate disposed between each resistance plate and the adjacent resistance plate, said contact plates being narrower than said resistance plates and being disposed in alignment so as to provide a rocking pivot for said stack of resistance plates, each of said resistance 75

plates having an end extending beyond its associated contact plates, the ends being normally spaced from each other by the contact plates between the resistance plates, a contact element mounted on each of said resistance plates spaced toward the ends of the plates from the contact plates, said contact elements being normally separated from each other and disposed to cause engagement of said contact elements each with the succeeding one as the stack of resistance plates is displaced about the pivot formed by the series of contact plates, such displacement causing variation of the contact resistance between the contact plates and the resistance plates, means whereby the speed of said drive motor is controlled by the effective resistance of the stack of contact plates and resistance plates, and means for varying the displacement of said stack of plates in accordance with the variations in the degree of deflection of the strip by said roller, whereby the deflection of the strip by the roller is kept within predetermined limits.

5. In a system for subjecting a strip of material to tension as it passes between adjacent roll stands of a strip rolling mill, comprising a tensioning roller disposed to be made to bear upon the strip to deflect it from its normal pass line between the roll stands and thus subject the strip to tension, means for actuating said roller to bear against the strip including means for automatically varying the transverse force applied to the strip by the roller in accordance with its strip deflecting operating position to subject the strip to a substantially constant tension, an electric drive motor for the rolls of one of the roll stands, a variable voltage generator for exciting said drive motor, a carbon-pile type rheostat connected to control the excitation of said generator, and means for varying the effective resistance of said rheostat in accordance with variations in the degree of deflection of the strip by said roller, whereby the deflection of the strip by the roller is kept within predetermined limits.

6. In a system for subjecting a strip of material to tension as it passes between adjacent roll stands of a strip rolling mill, comprising a tensioning roller disposed to be made to bear upon the strip to deflect it from its normal pass line between the roll stands and thus subject the strip to tension, means for actuating said roller to bear against the strip including means for automatically varying the transverse force applied to the strip by the roller in accordance with its strip deflecting operating position to subject the strip to a substantially constant tension, an electric drive motor for the rolls of one of the roll stands, a variable voltage generator for exciting said drive motor, a resistor connected in excitation controlling relation with said gen-

erator, a plurality of flexible members arranged with corresponding ends clamped in fixed relation and connected to separate points along said resistor, said fixed ends being insulated from one another, the other ends of said flexible members being free to move, a movement limiting stop against which the free ends of said flexible members are biased for positioning them in spaced relation, and means controlled in accordance with the degree of deflection of the strip for actuating said flexible members from engagement with said stop and into circuit closing engagement with adjacent members to short-circuit selected portions of said resistor to thereby limit the degree of deflection of the strip by said tensioning roller.

7. In a system for subjecting a strip of material to tension as it passes between adjacent roll stands of a strip rolling mill, comprising a tensioning roller disposed to be made to bear upon the strip to deflect it from its normal pass line between the roll stands and thus subject the strip to tension, means for actuating said roller to bear against the strip including means for automatically varying the transverse force applied to the strip by the roller in accordance with its strip deflecting operating position to subject the strip to a substantially constant tension, an electric drive motor for the rolls of one of the roll stands, a variable voltage generator for exciting said drive motor, a stack of resistance plates, a metal contact plate disposed between each resistance plate and the adjacent resistance plate, said contact plates being narrower than said resistance plates and being disposed in alignment so as to provide a rocking pivot for said stack of resistance plates, each of said resistance plates having an end extending beyond its associated contact plates, the ends being normally spaced from each other by the contact plates between the resistance plates, a contact element mounted on each of said resistance plates spaced toward the ends of the plates from the contact plates, said contact elements being normally separated from each other and disposed to cause engagement of said contact elements each with a succeeding one as the stack of resistance plates is displaced about the pivot formed by the series of contact plates, such displacement causing variation of the contact resistance between the contact plates and the resistance plates, means whereby the excitation of said generator is controlled by the effective resistance of the stack of contact plates and resistance plates, and means for varying the displacement of said stack of plates in accordance with the variations in the degree of deflection of the strip by said roller, whereby the deflection of the strip by the roller is kept within predetermined limits.

WILLARD G. COOK.
